UNITED STATES PATENT OFFICE.

REGINALD KERSHAW PIERSON AND THOMAS SMITH DUNCAN, OF WESTMINSTER, LONDON, ENGLAND, ASSIGNEES TO VICKERS LIMITED, OF WESTMINSTER, LONDON, ENGLAND.

TAIL SKID FOR AIRCRAFT.

Application filed June 21, 1921. Serial No. 479,308.

(GRANTED UNDER THE PROVISIONS OF THE ACT OF MARCH 3, 1921, 41 STAT. L. 1318.)

To all whom it may concern:

Be it known that we, REGINALD KERSHAW PIERSON and THOMAS SMITH DUNCAN, both subjects of the King of Great Britain, residing at Vickers House, Broadway, Westminster, in the county of London, England, have invented certain new and useful Improvements in or Relating to Tail Skids for Aircraft (for which we have filed an application in England No. 9,684, April 6, 1920), of which the following is a specification.

This invention relates to tail skids for aircraft such as flying boats or hydro-aeroplanes, the improved tail skid being more particularly intended for flying boats which are provided with landing gear for enabling them to alight on or start from the ground when desired.

According to this invention the tail skid is combined with or forms part of a rudder which is used for steering the flying boat when travelling in the water. The tail skid, which may be in the form of a pivoted shoe, may have secured thereto a casing which forms the water rudder and also constitutes a housing for a shock absorber with which the tail skid co-operates. The tail skid, the shock absorber and the water rudder constitute a compact unit which may be resiliently connected to the means for moving the air rudder of the flying boat so that the air rudder and water rudder can be moved simultaneously when steering the flying boat.

In order that the said invention may be clearly understood and readily carried into effect, the same will now be described more fully with reference to the accompanying drawings, in which:—

Figure 1 is a side view partly in section of one construction of the combined tail skid and water rudder fitted to a flying boat hull only a small part of which latter is illustrated.

Figure 2 is a plan view showing more particularly the shape of the water rudder.

Figure 3 is an enlarged detail view of part of the shock absorber.

Figure 4 is a small diagrammatic view showing the connection of the combined skid and water rudder to the rudder bar which controls the air rudder.

A is the tail skid which is in the form of a shoe having a suitable surface and shape for contacting with the ground. A' is a short tubular rod to the lower end of which the aforesaid skid or shoe A is secured, the upper end of this rod being pivotally connected to the lower end of a vertical rod B by means of flat interfitting lugs on the two rods A' and B and a horizontal pivot pin B'. The rod B is mounted in bearings or supports B² secured to the hull structure C in such manner as to be angularly movable 65 on a vertical axis within a casing or sleeve B³ which is secured to the hull and is carried to a point well above the waterline, thus obviating the necessity for a gland. By 70 reason of the above construction the skid A is capable of angular movement around a vertical axis as may be required when the flying boat is traveling along the ground and also of angular movement on a horizontal axis on the pivot pin B' when it cooperates with a shock absorber as hereinafter described. Secured to the tail skid A and to the rod A' is a rearwardly extending casing D which constitutes the main or lower part of the water rudder and which as shown is associated with an upper casing D' secured to the angularly movable rod B. The lower casing D normally projects slightly into the upper casing D' but is adapted to move to a substantial extent into the latter as shown in dotted lines in Figure 1 when the skid is moved upwardly the outer or rear part of the lower casing D being rounded as shown to permit movement of 75 the same into the upper casing D'. The two casings D and D' constitute the water rudder and can be moved together as a whole around a vertical axis when the rod B is angularly moved for steering the flying boat in the water. This movement is generally effected simultaneously with the angular movement of the air rudder D^x (see Figure 4) for which purpose the rod B may be suitably connected to the rudder bar B⁴ 80 by cables B⁵ having spring compensators B^{5x} to absorb shocks when the aircraft is "taxying." As shown in Figure 2 the two casings D and D' are of stream-line formation so as to offer minimum resistance when in the water and during flight, and this for-

mation also enables the shock absorber to be conveniently housed within the two casings. The shock absorber may be of any suitable or known type, and in the example shown 5 the shock absorber is of the "Oleo" type and comprises a cylinder E pivotally connected at its upper end to a pin F carried by a bracket F which is pinned or otherwise secured to the angularly movable rod B. The 10 cylinder E contains a piston E' fitting closely therein and having a plunger-like extension or lower part of reduced diameter which passes through the lower end of the cylinder E and which is surrounded by suitable packing rings E². The lower extremity of the piston extension is pivotally connected to the tail skid as shown at E³; thus the shock absorber is capable of being 15 moved with the combined tail skid and the rudder when the latter is angularly adjusted by the angular movement of the rod B. When the tail skid comes into contact with the ground and is moved upwardly the shock 20 is absorbed by the resiliency afforded by the compression of air within the cylinder E due to the upward movement of the piston which as shown is provided with a diaphragm E⁴ separating the space in the cylinder above the piston from the space in the piston extension. These two spaces however are in communication by means of a 25 tube E⁵ open at both ends and extending from the lower part of the piston extension 30 through the diaphragm E⁴ to a point slightly above the piston E'. A small quantity 35 of oil is contained in the cylinder above the piston and during the upward stroke of the piston the compression of the air 40 in the cylinder forces the oil through small aperture E⁶ in the piston into an annular space between the piston extension and the cylinder wall as shown in Figure 3; on the return movement of the piston due to 45 expansion of air in the cylinder the oil is gradually forced by the piston from the said annular space back into the cylinder through the aforesaid apertures E⁶ thereby causing the return movement of the piston to be 50 retarded. The piston extension also contains a small quantity of oil which during the return movement of the piston is forced by the expansion of the air in the piston extension upwardly through the tube E⁵ 55 into the space in the cylinder E above the piston thus replenishing any leakage of the oil in the cylinder. The level of the oil above the piston is determined by the height of the aforesaid tube E⁵ so that any excess 60 of oil forced into the cylinder from the piston extension is automatically returned by over-flowing through the tube E⁵ back into the piston extension. The main use of the tube E⁵ is to enable the piston extension to 65 serve as an additional air chamber, as

without this tube the said extension would merely contain useless oil.

What we claim and desire to secure by Letters Patent of the United States is:—

1. A combined tail skid and water rudder 70 for hydro-aeroplanes or flying boats, comprising a pivoted skid member having an extension, which constitutes the rudder or the main portion thereof.

2. A combined tail skid and water rudder 75 for hydro-aeroplanes or flying boats, comprising a movable skid member, and a rudder portion provided on said skid member, and adapted to be moved relatively to another rudder portion, which forms an 80 extension of the rudder portion on the skid so that two rudder portions form a water rudder of large area.

3. A combined tail skid and water rudder 85 for hydro-aeroplanes or flying boats, comprising a movable skid member, a rudder portion thereon, adapted to co-operate with another rudder portion, and a shock absorber with which the skid member co-operates, and which is contained in the two 90 rudder portions.

4. A combined tail skid and water rudder 95 for hydro-aeroplanes or flying boats, comprising a skid member provided with an extension forming a rudder portion, an angularly movable rod to which the forward end of the skid member is pivoted, a bracket on said angularly movable rod, and a shock absorber connected to said bracket and the rear part of the skid member.

5. A combined tail skid and water rudder 100 for hydro-aeroplanes or flying boats, comprising an angularly movable rod, a skid member pivoted on said rod, a rudder portion on said skid member, a rudder portion carried on said angularly movable rod, a shock absorber contained in said rudder portions which are of stream line formation.

6. A combined tail skid and water rudder 110 for hydro-aeroplanes or flying boats, comprising a skid member having a rudder and movable in two directions and a shock absorber movable with said skid in one direction and adapted to absorb shocks when the skid is moved in the other direction, said 115 shock absorber comprising a cylinder with a piston therein, the latter having a hollow extension in communication in the air space above the piston by means of a tube through which oil can be forced from the extension 120 into the cylinder above the piston.

7. A combined tail skid and water rudder 125 for hydro-aeroplanes or flying boats, comprising a movable skid member, a rudder combined and movable therewith, and means whereby the skid member with the rudder can be moved in unison with the air rudder of the flying boat.

8. A combined tail skid and water rudder 130 for hydro-aeroplanes or flying boats, com-

- prising a vertical rod angularly movable in supports on the flying boat structure, a skid member pivoted at its forward end to said rod, a bracket fixed to and movable with said rod, a shock absorber interposed between the rear end of the skid member and the said bracket, a water rudder movable with said skid and means whereby the said rod is connected to the means for moving the air craft rudder so that the said rod with the skid, shock absorber and water rudder may be moved simultaneously with the air rudder.
9. A combined tail skid and water rudder for hydro-aeroplanes or flying boats, comprising a vertically disposed rod angularly movable in supports on the flying boat structure, a skid member pivoted at the lower end of said angularly movable rod, a bracket fixed to and movable with said rod, a shock absorber interposed between the said bracket and the rear end of the skid member, a casing fixed on and movable with said rod, a casing fixed on and movable with said skid member and adapted to fit into the upper casing, the two casings forming a water rudder of stream line forma-
- tion and enclosing said shock absorber, and means connected to said rod and to the air rudder of the flying boat so that the skid member with the aforesaid shock absorber and water rudder can be moved simultaneously with the air rudder.
10. A combined tail skid and water rudder for aircraft comprising an angularly movable rod, a skid or shoe pivotally connected to the lower end thereof, a shock absorber interposed between said skid or shoe and a bracket on said rod, and a casing secured to said skid and adapted to co-operate or move relatively to an upper casing, the two casings constituting a housing for the shock absorber.
11. A combined tail skid and water rudder for aircraft comprising a skid bar capable of angular movement in two directions, a two-part casing, one part of which moves in one direction with said skid bar whilst the other part moves in both directions, and a shock absorber associated with said skid bar and housed in the said two-part casing.

REGINALD KERSHAW PIERSON.
THOMAS SMITH DUNCAN.
